Patented Dec. 29, 1914.

FIG. 1.

FIG. 2.

FIG. 3.

UNITED STATES PATENT OFFICE.

EDWARD EMANUEL AUGUST, OF CHICAGO, ILLINOIS.

RAIL-JOINT.

1,122,355.

Specification of Letters Patent. Patented Dec. 29, 1914.

Application filed August 5, 1914. Serial No. 855,243.

To all whom it may concern:

Be it known that I, EDWARD EMANUEL AUGUST, a citizen of the United States, residing at Chicago, in the county of Cook, 5 State of Illinois, have invented certain new and useful Improvements in Rail-Joints; and I do hereby declare the following to be a full, clear, and exact description of the invention, such as will enable others skilled 10 in the art to which it appertains to make and use the same.

This invention relates to certain novel and useful improvements in rail joints, and has particular application to means for connecting the meeting ends of the two rails so as to secure the same firmly together, and at the same time prevent the lateral displacement of the rails.

In carrying out my invention it is my 20 purpose to provide a simple, yet efficient form of rail joint, which may be readily assembled in position to couple the meeting ends of the rails, the joint being capable of ready removal when desired. At the same 25 time provision is made for locking the plates forming the joint in position so that the liability of the plates working loose is obviated.

With the above recited objects and others 30 of a similar nature in view, my invention consists in the construction, combination and arrangement of parts set forth in and falling within the scope of the appended claims.

35 In the accompanying drawings: Figure 1 is a side view of the meeting ends of two rails coupled by means of my improved joint. Fig. 2 is a cross sectional view taken on the line 2—2 of Fig. 1. Fig. 3 is a perspective view of one of the plates, showing the key slots therein. Fig. 4 is a longitudinal sectional view of a portion of the plate and showing the locking key in locking position and bearing against one of the coupling bolts.

Referring now to the accompanying drawings in detail, the letters A and B designate the meeting ends of two rails of well known form, such as railway rails. The 50 rails are provided with the usual bolt holes 1 formed in the webs.

The letters C and C' indicate two rail joint plates formed of any suitable material, such as metal and made sufficiently long to 55 overlap the meeting ends of the rails in the usual manner. Bolts D are threaded or

otherwise connected to the plate C' and are provided with heads d connected with the shanks by means of the reduced neck portions d'. The top and bottom longitudinal edges of the plate are beveled as at 3, so that the plate when fitted in position against the webs of the meeting ends of the rails will fit snugly in place and bear at its top and bottom edges against the undersides of the ball portions of the rails and against the top sides of the bases of the rails.

The inner side of the plate C is formed with a series of T-slots 4, that is to say, these slots are formed with relatively widened portions 5 adapted to receive the heads d of the coupling bolts of the joint, and relatively reduced or narrowed portions 7 in which the neck sections d' of the bolts lie when the plate has been driven home into coupling position. At this time, that is to say when the plate is in coupling position, the heads of the bolts lie beneath the overhanging flanges 8—8, forming the walls of the slots, the relatively narrow slot 9 formed by these flanges, permitting the passage of the neck portions d' of the coupling bolts.

From the description thus far given, it will be noted that when the meeting ends of the rails have been properly positioned and the coupling bolts passed through the webs thereof, the plate C may be applied, the widened mouths of the T-slots receiving the bolts. The plate is then driven or shifted longitudinally of the rail ends so that the flanges 8—8 will overlie the heads of the bolts.

In order to fasten the plate in position, I form in the plate a longitudinal threaded bore 10, which opens through one end of the plate and communicates with the T-slot nearest the end of the plate. A key shaft formed of a shank 11 and a head 12 is threaded into this threaded longitudinal bore, and screwed up until the end of the shank abuts against the head of the coupling bolt lying in the first slot, and this key is preferably made of such length that when fully screwed home the head 12 lies entirely within the socket 12' of the bore 100 95 105 and is concealed in the latter.

A small cap plate 13 is pivoted at the end of the plate over the entrance of the key bore, and this cap plate may be swung to cover the outer end of the bore and keep dirt and other foreign matter from working into the latter.

It will be seen that when the key is screwed home and bears against the head of the bolt, the plate is prevented from working or sliding back, and the liability of the plate being thus disengaged is avoided. It will further be seen that when the plate is in position and connecting the rails together, the bolt heads are concealed, and will be prevented from turning, so that the liability of the bolts working loose is avoided, and at the same time, by reason of the fact that the bolts are concealed by the plate, and the plate locked in position, the possibility of the coupling bolts being loosened or the joint being tampered with by unauthorized persons, is avoided.

While I have in the present instance shown the invention as applied to one side of the rail, it will of course, be understood that it may be applied to both sides of the rail as desired. When it is desired to remove the plate, as in replacing rails, it is only necessary to employ a tool for the purpose of unscrewing the key and working the same from the bore when the plate may be knocked outward by a blow upon one end of the same to remove the plate from the bolts.

It will be noted that I have provided an exceedingly simple, yet efficient form of rail joint which will not only secure the ends of the rails together and prevent the lateral displacement of such rails, but such plate forms a positive locking means for preventing the bolts from working loose.

What I claim is:

1. In a rail joint, the combination with rails having transverse openings in the webs thereof, of bolts passed through said openings, a plate having slots formed at the inner side thereof for the reception of the ad-

jacent portions of the bolts, said plate having a longitudinal bore therein communicating with one of the slots, and a key socketed in said bore and adapted to bear against a fastening bolt to hold the latter in its slot in the plate.

2. The combination with the meeting ends of a pair of rails, said rail ends having transverse openings in the webs thereof, of bolts passed through said webs, a plate having a series of T-slots formed therein for the reception of the heads of the bolts, said plate also having a longitudinally threaded bore opening through one end of the plate and communicating with the adjacent T-slot of the plate and a key threaded into the bore and adapted to bear at its inner end against the adjacent bolt to lock the plate in rail joining position.

3. The combination with the meeting ends of a pair of rails, said ends having transverse openings in the webs thereof, of bolts passing through said openings, of a plate lying against the webs of the rails, said plate having a series of T-slots therein for the reception of the heads of the bolts, said plate also having a longitudinal bore opening through one end of the plate, and communicating at its inner end with the adjacent T-slot, a key socketed in said bore and adapted to bear against the portion of the bolt lying in the slot with which the bore communicates, and a cap at the end of the plate for covering the entrance of the bore.

In testimony whereof, I affix my signature, in the presence of two witnesses.

EDWARD EMANUEL AUGUST.

Witnesses:

WASHINGTON BOSZOL,
GEO. S. ANDERSON.
